UNITED STATES PATENT OFFICE.

EUGENE MILES BARLER, OF HOUSTON, TEXAS.

SHADOWGRAPH.

1,263,307.

Specification of Letters Patent. Patented Apr. 16, 1918.

Application filed November 2, 1917. Serial No. 199,858.

To all whom it may concern:

Be it known that I, EUGENE M. BARLER, a citizen of the United States, and a resident of Houston, in the county of Harris and State of Texas, have invented certain new and useful Improvements in Shadowgraphs; and I do hereby declare the following to be a full, clear, and exact description of the invention, such as will enable others skilled in the art to which it appertains to make and use the same.

This invention relates to improvements in shadowgraphs,—the object of the invention being to provide simple and efficient means whereby various designs may be built up or assembled and supported in a manner to be disposed between a light and a screen so that the outline of the design shall appear as a shadow upon the screen.

20 A further object is to so construct a shadowgraph that any one of numerous designs may be created and serve to afford entertainment and amusement when the shadows of such designs are caused to appear on a screen or other surface.

With these and other objects in view, the invention consists in certain novel features as hereinafter set forth and pointed out in the claims.

30 In the accompanying drawings, Figure 1 is a view of a holder for pieces of which a design may be composed. Fig. 2 is a view illustrating the manner in which a design may be built up or assembled upon the holder. Fig. 3 is a view of an auxiliary holder. Figs. 4, 5, 6 and 7 are views of sheets containing separable pieces to be cut out and applied to the holder to form various designs, and Fig. 8 is a view of a shadow picture.

1 represents a holder which may consist of a plurality of superimposed sheets of cardboard or other suitable material. These sheets are made of various sizes and are set 45 cured together in a manner to leave their edge portions free and thus provide spaces into which pieces of cardboard or other material are inserted in building up a design, as illustrated in Fig. 2. The holder 1 may have a shape to provide a head portion 2, a neck portion 3, and a body or bust portion 4. The head portion 2 is made with a recess 5 in line with which the perforated portion of one of the pieces which go to make up the 55 design, may be disposed to represent an eye for example, as shown in Fig. 2.

The pieces 6 of which the design may be composed are made in numerous different shapes and these shapes are outlined on sheets of cardboard or other suitable material so that they may be readily cut out and applied to the holder 1 in building up any particular design which fancy may dictate. In Figs. 4, 5, 6 and 7, I have illustrated several sheets showing various shapes for the 60 pieces 6, but it is evident that other shapes or additional shapes of pieces 6 may be provided.

In some instances it may be desired, in building up a design, to employ more pieces 70 than the holder 1 will accommodate or to dispose some of such pieces in a manner which the holder 1, of itself, may not be readily adapted. In such case, I may employ a supplemental holder 7, such as shown 75 in Fig. 3. This holder comprises a plurality of sheets secured together leaving their edge portions free to receive pieces 6 and said auxiliary holder may be applied to the holder 1 in the same manner as are the 80 pieces 6.

When the design either of a head, an animal or other object shall have been built upon the holder 1 in the manner illustrated in Fig. 2, and the same is held between a 85 light and a screen or other surface, a shadow of the such design will appear upon the screen or surface as illustrated in Fig. 8.

Numerous changes may be made in the form and arrangement of the parts composing my shadowgraph and hence I do not wish to restrict myself to the precise details herein set forth.

For convenience I have applied numbers to the various pieces 6 on the several sheets 95 from which the design shown in Fig. 2 have been selected, the pieces 6 being numbered according to like pieces on said sheets.

Having fully described my invention what I claim as new and desire to secure by Letters-Patent, is:

1. A shadowgraph comprising a holder and a plurality of variously shaped pieces removably attachable to said holder to form a design.

2. A shadowgraph comprising a holder and a plurality of variously shaped pieces, said holder comprising a plurality of sheets secured together but having their edge portions free for the reception and retention 110 of said variously shaped pieces.

3. A shadowgraph comprising a main

holder, an auxiliary holder, and a plurality of variously shaped pieces, both of said holders constructed to receive and temporarily retain said pieces in position to form 5 a design, and said main holder adapted to temporarily support the auxiliary holder and the pieces carried thereby.

In testimony whereof I have signed this specification in the presence of two subscribing witnesses.

EUGENE MILES BARLER.
